FREE CHAIN HOIST

Filed August 1, 1924

Patented Apr. 13, 1926.

1,580,411

UNITED STATES PATENT OFFICE.

FREDRICK W. COFFING, OF PERRYSVILLE, INDIANA, ASSIGNOR TO OTTO WALTER, OF PERRYSVILLE, INDIANA.

FREE CHAIN HOIST.

Application filed August 1, 1924. Serial No. 729,490.

To all whom it may concern:

Be it known that I, FREDRICK W. COFFING, a citizen of the United States, and a resident of Perrysville, county of Vermilion, and 5 State of Indiana, have invented a certain new and useful Free Chain Hoist; and I do hereby declare that the following is a full, clear, and exact description thereof, reference being had to the accompanying drawings, in which like numerals refer to like parts.

This invention relates to a chain hoist of the free chain type, adaptable for selective step by step raising and lowering of a load 10 through a chain.

The chief object of the invention is to construct a hoist of a character that is adapted to have sufficient strength to sustain relatively heavy loads and be operable in a relatively simple manner.

The chief feature of the invention consists in the construction of the several parts of the free chain hoist whereby they are compactly arranged, few in number, and selectively operable.

Another feature of the invention consists in the arrangement of the several parts whereby the chain is caused to engage simultaneously at least two or more of the teeth 20 of the gear wheel actuating or moving said chain.

Another feature of the invention consists in the arrangement of the housing for the chain and the gear wheel in two complementary parts which form a relatively closed and unobstructed chain receiving channel and an enclosed gear chamber.

In addition thereto said housing is adapted to rotatably support a supporting hook 40 and a suitable mechanism is associated therewith for securing said hook in any one of a plurality of predetermined positions.

Another feature of the invention consists in the provision of means whereby certain parts are maintained in a predetermined position for continuous ratcheting movement as will be pointed out more specifically hereinafter.

Another feature of the invention consists 50 in the provision of a lever or actuating handle which includes a unitary housing adapted to protect or partially incase suitable control and operating mechanism associated with the gear wheel and for controlling and actuating the same.

The full nature of the invention will be understood from the accompanying drawings and the following description and claims:

In the drawings Fig. 1 is a side elevational view of one-half of the chain construction illustrating certain parts and with a portion hereof in section to illustrate other parts in detail. Fig. 2 is a side elevation of the hoist including the lever handle with parts 60 broken away to show other parts in detail. Fig. 3 is an elevational view of the handle and a portion of the gearing associated therewith. Fig. 4 is a view similar to Fig. 1 and of the gear portion thereof. Fig. 5 is a view 65 similar to Fig. 4 and illustrates the parts in another position.

In the drawings 10 indicates an elongated channel which has an inclined wall 11 and an outlet 12. The channel also includes an 70 abutment 13 and an arcuate portion 14 which has a mouth 15. Associated with the arcuate portion 14 is a substantially circular portion 16 which constitutes the sprocket chamber. A shaft 17 is pivotally supported in 75 the housing and carries a sprocket pinion 18 adapted to engage the links of the chain 19. The abutment 13 causes the chain 19 to describe a curve and thus, as shown clearly in Fig. 1, causes two of the teeth on the sprocket 80 pinion 18 to engage the links of the chain 19, thereby dividing the load supported by the chain among the two teeth.

It will be readily observed from Fig. 1 that the chain 19 lies in an enclosed and 85 substantially free channel extending approximately from end to end of the body portion. Herein the upper end of the chain is shown provided with a stove bolt 20 that passes between the side links and the two 90 pins defining an opening, and said bolt carries a nut 21. The bolt and nut construction thus positioned acts as a stop to prevent additional movement of the chain thru the housing until said stop is removed from 95 the chain which can be very readily accomplished.

As shown clearly in Figs. 1 and 2 the channel 10 is formed by a body portion comprising two halves which are defined by 100 median and facing peripheral flanges 22. Said flanges 22 are suitably secured together by means of the screw bolts and nuts 23 and 24 respectively. With the foregoing arrangement it will be readily apparent the 110

- housing may be quickly opened and access had thereto. Herein the end opposite the sprocket gear chamber 16 is shown including a chamber 25 with a reduced neck 26. 5 A hook 27 has enlargements 28 and 29 spaced by a neck 30 seatable in the neck 26. The body portion supports a plunger 31 having a stem 32 about which is coiled a spring 33 for normally forcing said plunger inwardly. 10 A handle or finger piece 34 is positioned exteriorly of the casing and is adapted to retract the plunger 31 in opposition to the spring 33 and permit free rotation of the hook 27. When it is desired to secure the 15 hook 27 in any one of a plurality of predetermined positions, the finger piece 34 is released and the plunger 31 is projected inwardly to engage one of the notches carried by the enlargement 29. Thus the hook 27 is secured in the desired rotative position. Reference will now be had to the several figures and particularly those portions thereof which illustrate the actuating and control mechanism for actuating and controlling the sprocket pinion 18 mounted in the chamber 16 upon shaft 17. Concentric with the bearing receiving the shaft 17 there is provided a stationary ratchet 36 which herein is shown recessed or cut away as of 37. 20 Oscillatably mounted upon the shaft 17 and closing said recess or chamber 37 is a plate 38 having formed upon its periphery ratchet teeth which are adapted to register with the ratchet teeth 36 or be slightly offset therefrom. Upon the extended end of the shaft 17 there is suitably secured as by being keyed, or the like, a driving ratchet 39. The ratchet 39 is reduced and forms a bearing portion 40. A lever or handle construction 25 consists of a gradually tapering channel 41, which includes a tubular bearing portion 42 rotatably supported upon the bearing portion 40 and secured in position by a retaining plate 43 and nut 44 upon the reduced and threaded end 45 of the shaft 17. A shoulder 46 (see Fig. 2) is adapted to anchor the foregoing construction in associated relationship upon the housing.

Pivottally supported by the channel-shaped lever or handle at 46' is a dog or latching member 47 having a locking tooth 48, which tooth is adapted to engage the teeth of the ratchet 36 and also the teeth of the ratchet 38. A rod 49 is connected to said dog 47 or pawl and also to a bell crank lever 50, pivotally supported adjacent the end of the handle, and provided with a hand engageable portion. Elevation of the latch 47 into the pocket 151 out of the path of the ratchet teeth 36 and 38 is secured by actuating the bell crank lever 50. Reference will be had hereinafter to the further relative movement of the ratchets 36 and 38 and the locking tooth 48.

15 The handle 41 also pivotally supports a

lever 51 connected by a link rod 52 which is slidably associated with an ear 53 carried by a dog or pawl 54 pivotally supported at 55 by the lever or handle 41. A spring 56 is secured in coiled position by a retainer 57 carried by the rod 52. Spring 56, therefore, is interposed between the projection or ear 53 and the retainer 57. Actuation of the lever 51, therefore, is adapted to disengage through the action of spring 56 the pawl 54 from the sprocket pinion 39, likewise overrunning of the pawl with respect to said sprocket is permitted by reason of this spring connection.

Pivottally supported in the chamber 16 (see Figs. 1, 4 and 5) is a dog 60 which has a locking face 61. Said dog is normally maintained in position to engage one of the teeth of the pinion 18 by a spring 62 having its free ends positioned in recesses 63 and 64 formed in the dog and the housing respectively. When the lever or handle 41 is moved arcuately and in the direction of the arrow, as shown in Fig. 3, the detent or dog 54 engages a tooth of sprocket 39 and the shaft 17 is rotated. Rotation of shaft 17 carries with it the pinion 18 and this in turn moves the chain upwardly to elevate the load. At the same time, the tooth next to or adjacent the dog 60 engages the same and cams it out of the way in opposition to spring 62. After the tooth has passed from beneath the dog the same is projected into locking engagement with the rear face of the camming tooth by reason of spring 62. This action continues so long as the handle movement is continued in the direction indicated by the arrow in Fig. 3.

Upon reverse movement of the handle it will be apparent that the dog 54 overruns the ratchet 39. Upon such reverse movement the load, however, acting through the pinion 18 causes a tooth thereof to engage the face of the locking dog 60 and thus hold the pinion against reverse rotational movement and thereby support said load in the elevated position. From the foregoing, therefore, it will be understood that the free chain hoist may operate in elevating the load with one, two or more ratchet teeth advancement at each operation of the lever.

Reverse or lowering movement is as follows: The plate 38 covering chamber 37 includes a lateral projection 70 and this projection 70 carries a pin 71 which is engaged by a spring 72 positioned within the chamber 37. The wall between chamber 16 and chamber 37 is provided with an arcuate opening 73 and a portion of said extension 72 passes through said arcuate opening and limits the rotational movement of the plate 38 to that defined by the arcuate opening. The extending end of the projection 72 is adapted to engage an ear or projection 74 carried by a dog or detent 60. The action

- is as follows: Upon the initial reverse movement of the handle the tooth 48 engages the adjacent teeth upon the ratchets 36 and 38 and causes said ratchet teeth to register. 5 Such registration retracts the pin 72 from the lowermost position into its uppermost position in opposition to spring 72. This permits dog 60 in chamber 16 to engage the adjacent pinion tooth and take the load, said 10 dog being maintained in this position by the spring 62. With the load thus sustained, the lever is reversely rotated and again positioned with the tooth 54 engaging one of the teeth of the ratchet 39.
- 15 The load is thereupon transferred to the handle by the actuating mechanism including the dog 47 and the load is lowered as the lever is turned. Actuation of lever 50 during the reversing or repositioning of the 20 lever 41 permits locking tooth 60 to hold the load while the lever is being repositioned with respect to the ratchet 39. After repositioning the lever 50 is released which permits the plate 38 to be repositioned under 25 influence of spring 72 and at the same time removes the locking dog 60 from locking engagement, thereby throwing the load into the handle instead of onto the housing. Reverse movement of the handle thereupon 30 will permit the load to lower the chain by permitting the rotation of the sprocket as the handle is actuated. It will be noted that the release or lowering movement may be in varying amounts for one or more teeth on 35 the ratchet 39 if desired.
- Pivottally supported at 80 in the housing is a locking lever 81 having finger engageable portion 82 and a locking portion 83. Said locking portion 83 is so associated with the 40 aforementioned mechanism that actuation of the same through the lever 50 is not required in the lifting movement of the chain when the locking lever 81 is positioned as shown in Fig. 4. Fig. 5 shows the same parts in the 45 released position, that is in the inoperable position. It will be noted that lever 81 is so arranged that when placed in the position shown in Fig. 4 locking portion 83 holds projection 70 back so that plate 38 is stationary. Thus there is provided a plain 50 ratchet in the lifting movement but cannot be used in the lowering movement. Thus in the elevating movement the aforesaid prevents the use of pawl 48.
- 55 The invention claimed is:
1. In a chain hoist the combination of a
- housing having an elongated channel portion therein, a circular chamber portion tangential thereto, an offset portion in said channel inclined to the elongation and the 60 chamber for forming an abutment therebetween adjacent said chamber and another channel portion substantially in line with the first mentioned portion and tangential to the chamber portion, a pinion in said 65 chamber with its axis coincident therewith, and a chain in said channel and chamber having simultaneous engagement with a plurality of pinion teeth by reason of said offset abutment. 70
2. A device as defined by claim 1, characterized by said housing including a socket in alignment with the elongated channel portion, and a hook swivelably supported in said socket with its axis also in alignment 75 with said elongated channel portion.
3. In a free chain hoist the combination of a chain, a pinion for operating said chain, a shaft supporting said pinion, a ratchet supported by said shaft for rotating the 80 same, a ratchet concentric with the shaft and stationary with the housing, a registerable ratchet oscillatably supported adjacent the first mentioned ratchet, and a handle mechanism associated with the three ratchets. 85
4. In a free chain hoist the combination of a chain, a pinion for operating said chain, a shaft supporting said pinion, a ratchet supported by said shaft for rotating the 90 same, a ratchet concentric with the shaft and stationary with the housing, a registerable ratchet oscillatably supported adjacent the first mentioned ratchet, and a handle mechanism associated with the three ratchets and adapted to enclose the same. 95
5. In a free chain hoist the combination of a chain, a pinion for operating said chain, a shaft supporting said pinion, a ratchet supported by said shaft for rotating the 100 same, a ratchet concentric with the shaft and stationary with the housing, a registerable ratchet oscillatably supported adjacent the first mentioned ratchet, a handle mechanism associated with the three ratchets and adapted to enclose the same, and other means 105 associated with said pinion for controlling the same independent of the ratchet mechanism.

In witness whereof, I have hereunto affixed my signature.

FREDRICK W. COFFING.
